Inventor:-

J. JUDGE

By his Attorney:- H. L. TUNA

UNITED STATES PATENT OFFICE.

JOHN JUDGE, OF MANCHESTER, ENGLAND.

COMMUTATOR OR ROTARY IGNITION-CURRENT DISTRIBUTOR FOR INTERNAL-COMBUSTION ENGINES.

Application filed August 22, 1922. Serial No. 583,583.

To all whom it may concern:

Be it known that JOHN JUDGE, a subject of the King of Great Britain and Ireland, residing at Manchester, England, has invented new and useful Improvements in Commutators or Rotary Ignition-Current Distributors for Internal-Combustion Engines, of which the following is a specification.

10 This invention relates to commutators or rotary ignition current distributors for internal combustion engines and has for its object to provide an improved form of distributor primarily designed for Ford cars.

15 According to the invention the distributor casing is formed of suitable insulating material such as stabalite recessed on the inside to receive the distributor in the form of a disc of insulating material adapted to be

20 keyed to the engine cam-shaft. The outer face of the disc is provided with an all around metal track formed in segments, one of which is in electrical connection with the cam-shaft while the others constitute a

25 metal track for a series of carbon brushes slidably mounted in the adjacent face of the recessed casing. Said brushes are mounted in metal tubes let into the casing and connected to the respective terminals, and

30 springs are provided normally forcing the brushes into contact with the metal track on the rotor. The casing is provided with a metal centre on the exterior adapted to be engaged by a spring pressed arm to keep the

35 same in position and also with means for connection to the control lever for timing.

The invention will be more particularly described by the aid of the accompanying drawings, in which:—

40 Fig. 1 is a sectional elevation of the improved distributor shown applied to the cam or timing shaft of the engine.

Fig. 2 is a front elevation and

45 Fig. 3 a rear elevation of the distributor casing detached.

Fig. 4 is a sectional view of the distributor casing on the line 4, 4, and

Fig. 5 is a face view of the rotor detached.

50 Referring to the drawings the distributor casing *a* is formed of stabalite with a recess to receive the rotor or distributor disc *b* also formed of stabalite. The latter is secured to a metal hub *c* to fit the cam shaft *d*

and a metal peg *e* serves to place a segment 55 *f¹* of a metal ring *f* in electrical connection with the hub *c* and shaft *d*. The metal ring *f* is divided into four segments *f¹*, *f²*, *f³*, and *f⁴* of which the segment *f¹* is the current conveyor while the other segments constitute a 60 continuous metal track for the carbon brushes *g*, hereinafter referred to, all the segments being insulated from each other. The segments *f²*, *f³* are interposed between the segments *f¹* and *f⁴* so that the gap between the segments may be sufficiently narrow to allow the beforementioned brushes to always rest upon the metal ring without completing the circuit through any of the brushes except the one contacting with the 70 segment *f¹*.

The casing *a* is provided with a series of metal fittings *h* moulded therein, each fitting being formed with a tubular fitting *i* at one end lying transversely of the casing 75 and extending to the inner face of the casing. The four fittings *h* are arranged with their tubular ends *i* lying in a circle corresponding to the metal ring *f* on the rotor and set at points 90 degrees from each. The 80 other ends of the fittings *h* are continued to the periphery of the casing at the top side as seen in Figures 2 and 3 where they are bored and tapped to receive metal terminal screws. The latter are preferably numbered 85 and formed with heads of stabalite or the like of different colors for identification purposes.

Located in the tubular sockets *i* are a series of carbon brushes *g* normally forced 90 outwards into contact with the metal race *f* by means of the springs *j*.

The inner edge of the casing *a* is provided with a metal ring *k* secured thereto during the course of manufacture and with a metal 95 centre *l* at the apex of the conical back of the casing to receive the end of the spring securing arm, whilst an extension or lever *m* formed in one with the casing is provided with a metal brush to which is attached the 100 timing control link or lever.

In practice the rotary distributor disc *b* is fixed to the cam-shaft of a Ford engine and the distributor casing *a* placed thereon with the carbon brushes, resting upon the 105 segmental track *f*. Ignition leads are attached to the correct terminals and said terminals are screwed into the respective fit-

ting *h* terminating in holders for the brushes *j*. The usual pull rod connection is connected to the end of the lever arm *m*.

When the engine is started the metal segment *f* makes contact with one of the brushes *j* and the ignition lead attached to the respective fitting *h* is then in circuit with the cam-shaft. Immediately the segment *f* leaves the particular brush, the respective ignition circuit is broken, the ignition circuit for each brush being made and broken as the segment *f* contacts with and leaves the particular brush.

Preferably the terminal heads are colored to agree with the different colors of insulating covering of the leads. Or the name of the lead is on the terminal along with the number.

It will be understood that instead of carbon brushes, brushes of copper or other suitable material may be provided.

By these means very efficient distributors are provided which are smooth running in action and have a long life.

25. What I claim is:

1. Commutators or rotary ignition current distributors comprising an outer casing formed of insulating material recessed to receive a rotary distributor disc, a series of

brushes slidably mounted in said recess, a 30 rotary distributor disc, a metal ring formed in segments secured to said disc and with one segment electrically connected to the source of electrical current, said ring constituting a continuous metal track for the 35 brushes on the casing, substantially as described.

2. Commutators or rotary ignition current distributors comprising an outer casing formed of insulating material recessed to receive a rotary distributor disc, a rotary distributor disc, a metal ring formed in segments secured to one face of the disc, one segment being electrically connected to the source of electrical energy and all the segments being insulated from each other, a series of tubular fittings in the casing and a series of brushes slidably mounted in said tubular fittings so as to be capable of movement perpendicular to the face of the disc in 50 contact with the metal ring and supplemental terminals in electrical communication with the tubular fittings, substantially as described.

In testimony whereof I have signed my 55 name to this specification.

JOHN JUDGE.
